United States Patent Office

Des. 189,321
Patented Nov. 22, 1960

189,321

JAR OR SIMILAR ARTICLE

Brooks D. Fuerst, Sylvania, Ohio, assignor, by mesne assignments, to General Foods Corporation, White Plains, N.Y., a corporation of Delaware

Filed Dec. 30, 1959, Ser. No. 58,856

Term of patent 14 years

(Cl. D58—25)

FIG. 1

Figure 1 is a side elevation view of a jar or similar article showing my new design.

The side not shown is the same as the side shown.

The design for the jar disclosed is characterized by the disk-like members at the lower sides thereof having the configurations as shown.

I claim:

The ornamental design for a jar or similar article, as shown and described.
